SHEET OF PAPER TOWELING

Ikki Matsumoto, Loveland, Ohio, assignor to The Procter
& Gamble Company, Cincinnati, Ohio

Filed July 10, 1974, Ser. No. 487,428

Term of patent 14 years

Int. Cl. D5—06

U.S. Cl. D59—2 B

The figure is a plan view of a sheet of paper toweling showing my new design.

I claim:

The ornamental design for a sheet of paper toweling, substantially as shown and described.
